13 Claims. (Cl. 230—101)

The present invention relates to single- and multi-stage vapor-entrainment or condensation pumps and more particularly to a novel arrangement of a heating system providing very short heating and cooling periods in such pumps.

It is known that in condensation-type pumps the entraining fluid is heated to evaporation and then conveyed in a gaseous state, from the boiler to the ejector nozzle with a view to achieving the pressure required for the operation of the pump. Upon leaving the nozzle, the vaporized fluid condenses on the enclosure walls, which are usually cooled by extraneous means, after which the fluid returns in a liquid state to the reservoir or boiler.

In this type of arrangement it cannot be avoided that almost the entire amount of fluid has to be maintained at a relatively high evaporating temperature in the boiler although only a small portion thereof is being evaporated for use at any given moment. Consequently, it takes a long time to heat up and to cool down the pump, resulting in difficulties which are particularly evident in case of intermittent use. Various diffusion pumps have been designed which incorporate special fast-cooling devices in an attempt to overcome these difficulties.

The heat losses in these vapor-entrainment pumps originate not only from the necessity of removing the heat stored in the fluid but also from excess evaporation of the entire fluid surface. This circumstance also results in undesirable heat losses of the vapor which becomes unnecessarily cooled on its way to the ejector nozzle.

It is an object of the present invention to provide a novel vapor-entrainment pump overcoming the difficulties and drawbacks experienced with previous arrangements. In particular, object is to provide in such systems a special delivery pump for conveying the entraining fluid to a region of the vapor-entrainment pump close to the nozzle where the localized heating and evaporation takes place.

It is another object to provide a vapor-entrainment pump wherein the riser tube leading to said region of localized heating is cooled so as to return as much entraining fluid as possible to the boiler.

The present invention represents a simple yet effective solution of the drawbacks characteristic of hitherto known types of condensation or vapor-entrainment pumps. One of the main features of the invention resides in the provision and disposition of the heating means adjacent the nozzle or nozzles of the pump, adjacent the zone of use, rather than around or within the fluid reservoir or boiler, remote from the zone of use. A conventional type of delivery pump may be used for raising the fluid from the reservoir to the region of the heating means.

It is a further object of the invention to provide a cooling jacket around the riser tube of the delivery pump and/or an overflow tube which returns the excess fluid from the ejector means to the reservoir.

In a preferred embodiment using a conductive liquid metal, e.g. mercury, an electromagnetic pump is provided for conveying the entraining fluid to a small pool adjacent the combined heating and ejector unit. Advantageously, the fluid in such a small pool can be heated by passing an electric current through the conductive liquid.

The invention offers several advantages over previous systems. The most marked difference is that the entire volume of fluid contained in the reservoir cools down to the coolant temperature shortly after the vapor-entrainment pump is disconnected. There is no need for compensating temperature differences between the heater at the bottom of the boiler and the cooling jacket.

It is a further advantage of the arrangement of the present invention that the operating pressure at the ejector nozzle, or at each of several nozzles of multi-stage systems, is simple to regulate. The vapor-pressure regulation has a negligibly small time constant due to the low heat capacity of the heated parts. Moreover, the heating of each separate nozzle stage in the multi-stage embodiment, can be controlled individually.

In multi-stage vapor-entrainment pumps equipped with one or more stages, according to the present invention, the quantities of entraining fluid supplied to the individual stages can be easily adapted to the actual consumption.

These and other features and advantages of the invention will become more apparent in the following description and the enclosed drawings, in which:

FIG. 1 is a partly schematic sectional view of a preferred embodiment of a single-stage vapor-entrainment pump according to the invention;

FIG. 2 is a similar view of a vapor-entrainment pump using an electrically conductive liquid metal as the entraining fluid; and

FIG. 3 shows a schematic arrangement of a multi-stage vapor-entrainment pump having a high-pressure fore-vacuum stage connected in series with two diffusion-type stages.

In FIG. 1, the vapor-entrainment pump is shown to comprise a housing or shell 10 enclosing an inner shell 10a having a lower portion which forms a reservoir 11 containing the entraining fluid 12, which may be an oil having low vapor pressure, as generally used in diffusion pumps. The space between the shell and the housing serves as a cooling jacket 13 provided with an inlet 13a and an outlet 13b through which a coolant is circulated. A conduit 14 serves to connect the entrainment pump to a suitable source to establish a fore vacuum (not shown), while a conduit 15 provides a high-vacuum connection through which the pump may be connected to the system to be evacuated.

Above the reservoir 11, a delivery pump 16 is arranged within the inner shell 10a, with its inlet tube 16a reaching into the fluid 12 in the reservoir 11 and with its outlet tube 16b rising substantially centrally within the shell 10a to the region of the ejector 17. The unit 17 is preferably supported by flanges 17a and 17b attached to the cover portion of housing 10. The ejector unit 17 has a recessed portion 17c holding a pool 18 of the entrainment fluid supplied by the outlet or riser tube 16b of delivery pump 16. A heater 19, shown here as a double annular electric heating element, fed from a source of current 21 through a variable resistor 22 or other conventional means, is disposed to heat the liquid in the pool 18. The ejector 17 also has one or more nozzles, two of which are shown at 20a and 20b. The delivery pump 16 is energized from an electric source 23; this may be separate from or identical with the source of current 21 for the heater.

The ejector unit 17 may be provided with an overflow tube 24 the upper end of which is flush with the fluid level in pool 18. Both the overflow tube 24 and the riser tube 16b of delivery pump 16 can be provided with cooling jackets 25a, 25b, respectively. These cooling systems may, of course, be operated parallel with or independently from the cooling system of jacket 13 of the housing 10.

Before starting the vapor-entrainment pump, a fore vacuum is established at the connection 14 by means of a suitable external backing pump (not shown). Once the gas within the inner shell 10a is rarefied to a desired extent, the delivery pump 16 and shortly thereafter the heater 19 are put into operation. The fluid 12 in reservoir 11 will remain substantially at its original temperature, while the fluid in pool 18 of the ejector unit 17 will be heated sufficiently to be vaporized, and the vapor will emerge, in the form of streams through the nozzles 20a, 20b. The vapor streams trap the molecules of gas or air originally in the inner shell 10a, and those which diffuse into the shell from the system to be exhausted. The downward moving vapor streams carry the air or gas down to the region where the fore-vacuum pump is effective to remove the gas and pass it to the atmosphere. Relatively high vacua can be obtained with this single-stage vapor-entrainment pump system.

The cooling jacket 13, aided by the optional jackets 25a, 25b, condenses the vapor streams which thus return in liquid state along the inner walls of the shell 10a into the reservoir 11. The entraining fluid is consequently used over and over.

By heating only the small volume of liquid in pool 18 to generate the vapor streams, the large reservoir of liquid and the housing structure, generally, will be normally held at relatively low temperature. The entire apparatus may then be quickly restored to ambient temperature at the conclusion of an operation. This represents an important feature of the invention.

In FIG. 2, another embodiment of a single-stage vapor-entrainment pump is shown, where a conductive liquid metal, e.g. mercury, is used for entrainment. Here the housing or shell 50 has a narrow bottom portion 51 serving as a reservoir for the mercury 52. The cooling jacket 53 has an inlet 53a and an outlet 53b arranged in a fashion similar to that shown in FIG. 1, with the difference, however, that the jacket of this embodiment surrounds only the upper portion of the pump structure 50. The fore-vacuum and high-vacuum apertures are designated 54 and 55, respectively.

In this system, an electromagnetic pump 56 is applied to raise the mercury 52 from the reservoir 51 into a tube 56b. The pump 56 comprises an armature 56c which carries a coil 56d which is fed from an A-C. electric source 63. The alternating magnetic field between poles 56e of the armature 56c imparts a pulsating motion to the mercury within a throat 56f of the tube 56b, whereby the mercury is forced up through the tube 56b into a pool 58 in a recessed portion 57c of the ejector unit 57. In this embodiment, the mercury in the pool 58 is heated by means of an arc discharge produced between an electrode 59a reaching into the pool 58 and the mercury itself; the current is led from a source of current 61 through a regulator means 62 to the electrode 59a on the one hand and to the ejector-unit body on the other, the latter being provided with a terminal 59b. Electrode 59a is insulated from the unit 57; terminal 59b with the corresponding pole of source 61 is kept at ground potential, so that there will be no interference with other electrically conducting parts.

The ejector unit 57 has nozzles 60a, 60b and an overflow tube 64 carrying the excess mercury back to the reservoir 51. In this embodiment, no additional cooling jackets are shown for the tubes 56b and 64, although, it is to be understood, the cooling effect can be achieved in the same manner as in the previous illustration.

The vapor-entrainment pump, according to the present invention, may also be arranged in a single stage or in several stages of a multi-stage pump, as schematically illustrated in FIG. 3. This embodiment is provided with a preliminary liquid-jet stage 77, an optional vapor- or liquid-jet stage 87 and two diffusion stages 97 and 97', both of the latter being similar to the ejector unit 17 shown in FIG. 1. The stage 77 has a construction 80

for the passage of the entraining fluid; stages 77 and 87 are connected in series with the following parallel-acting stages 97 and 97'. Except for the liquid-jet stage 77, all the remaining stages are supplied by a delivery pump, or pumps 76 which have an inlet tube 76a reaching into the fluid 72 contained in a reservoir 71, these elements being similar to the respective elements 16, 16a, 12 and 11 of the first-described embodiment. In a similar way, the pump housing or shell 78, the cooling jacket 73, its connections 73a, 73b, the fore-vacuum connection 74 and the high-vacuum aperture 75 all correspond to their counterparts 10, 13, 13a, 13b, 14 and 15, respectively, of the first embodiment.

Owing to constricted nozzles 90a and 90b of the vapor-jet stage 87, this stage may be operated at a high pressure. An ample amount of entraining fluid is supplied by the delivery pump, or pumps 76 through a riser tube 86b. Similar and parallel riser tubes 95b and 95b' are provided from the same delivery pump, or pumps to the diffusion stages 97 and 97', respectively. All riser tubes have respective valve means 81, 91 and 91' individually operable through electrical or mechanical control means schematically indicated at 92. It is to be understood that the multi-stage vapor-entrainment pump may be a single pump or comprise a plurality of pumps 76 as indicated above.

The diffusion stages 97 and 97' have nozzles 100a, 100b and 100a', 100b' similar to the nozzles 20a and 20b shown in FIG. 1. Each of the stages 87, 97 and 97' has heating elements 89, 99 and 99', respectively, similar to the heater 19 described in connection with FIG. 1. For the sake of clarity, the supporting flanges 17a, 17b, the electric connections 21-23 to the heaters, and other structural details of FIG. 1 have been omitted from the somewhat schematic showing of FIG. 3.

When the heating element 89 of stage 87 is disconnected, this stage will perform as a liquid-jet stage; with the heater on, the fluid 72 will be vaporized as in the diffusion stages, so that the nozzles 90a, 90b will perform as vapor jets.

In a multi-stage entrainment pump according to this invention, a very high pumping stability is attained owing to the provision of the adjustable valve means 81, 91, 91' which will allow the required individual pressure values to be maintained for all stages without overloading them. The stability can be increased by incorporating suitably selected flow resistances into the fluid riser tubes or by other control means, e.g. by providing the riser tubes with predetermined cross sections.

It will be obvious to those skilled in the art that various changes and modifications may be made in the vapor-entrainment pumps according to this invention without departing from the invention in its broader aspects. It will be appreciated, for example, that the conveying, heating and ejector means may be substituted by other equivalent means, e.g. a high-frequency heater or a steam coil may be used, fed by respective external sources. Also, the last-described embodiment may be provided with one or more cooling jackets 85 and/or overflow tubes 84 for the individual stages, as shown in FIG. 3. These and other modifications shall be considered as falling within the scope of the invention.

What is claimed is:

1. A vapor-entrainment pump for rarefying gases, comprising an enclosing shell, a reservoir in the lower portion of said shell, a vaporizable fluid in said reservoir, ejector means for the vapor thus obtained in said upper portion of said shell, said shell having, below said ejector means, a fore-vacuum port connectable to an external pressure-reducing means of a known type, and having, above said ejector means, a low-pressure port connectable to the system to be evacuated, intermediate storage means between said lower and upper portions of said shell, fluid conveying means between said reservoir and said intermediate storage means for raising said fluid from said

reservoir to said intermediate storage means, said intermediate storage means being in fluid communication with said ejector means, heating means provided for said fluid in said intermediate storage means to vaporize said raised fluid, whereby the vapor leaving the ejector means will entrain molecules of the gas within the pump and guide them down to the region of the fore-vacuum port through which they are passed to the atmosphere, and a cooling jacket surrounding at least said upper portion of said shell and adapted to condense said vapor into fluid for return into said reservoir, and only a small proportion of the total amount of said vaporizable fluid is heated at one time.

2. A vapor-entrainment pump, according to claim 1 wherein said conveying means for the fluid comprises a centrifugal pump, an inlet tube of said pump reaching into said reservoir and an outlet tube of said pump being connected to said intermediate storage means.

3. A vapor-entrainment pump, according to claim 1, wherein said conveying means comprises a fluid displacement pump, an inlet tube of said pump reaching into said reservoir and an outlet tube of said pump being connected to said intermediate storage means.

4. A vapor-entrainment pump, according to claim 1, further comprising cooling means disposed adjacent to at least part of said conveying means, for accelerating the condensation of said vapor after it emerges from said ejector means.

5. A vapor-entrainment pump, according to claim 1, further comprising an overflow tube leading from said intermediate storage means to said lower portion of said shell, whereby the excess quantity of the fluid raised by said conveying means is returned to said reservoir.

6. A vapor-entrainment pump, according to claim 5, further comprising a second cooling jacket around said overflow tube for equalizing the temperature difference of said fluid within said reservoir and said ejector means.

7. A vapor-entrainment pump, according to claim 1, wherein said fluid is a conductive liquid metal, and said conveying means comprises an electromagnetic pump for raising said liquid metal from said reservoir to said ejector means, an inlet tube of said pump reaching into said reservoir and an outlet tube of said pump being connected to said intermediate storage means.

8. A vapor-entrainment pump, according to claim 7, wherein said heating means comprises at least one electrode connected to a source of electric current and contacting a pool of said liquid metal within said intermediate storage means so as to vaporize said liquid metal.

9. A vapor-entrainment pump for rarefying gases, comprising a pump shell, a reservoir in the lower portion of

said shell, a vaporizable fluid in said reservoir, a plurality of ejector stages within said pump shell, each having fluid storage and heating means for storage and heating of part of said vaporizable fluid, separately controllable conveying means for said fluid storage means of each of said plurality of ejector stages, delivery pump means adapted to deliver said vaporizable fluid to the fluid storage means of said ejector stages via said conveying means, a high-pressure port in said shell below said ejector stages, said high-pressure port being adapted to be connected to an external pressure reducing means of a known type, and a low-pressure port above said ejector stages, whereby said part of said fluid in said storage means of at least one of said ejector stages is vaporized by said heating means associated with said storage means and the fluid becomes vaporized and said vaporized fluid is emitted through the ejector stage to entrain gas molecules sucked through said low-pressure port and pass them through said high-pressure port.

10. A vapor-entrainment pump, according to claim 9, wherein said controllable conveying means comprises inlet tube means of said delivery pump means reaching into said reservoir and a plurality of outlet tubes of said delivery pump means, each outlet tube being connected to one of said ejector stages, and control means for regulating the amount of fluid delivered by said delivery pump means to each of said ejector stages.

11. A vapor entrainment pump according to claim 10, wherein said delivery pump means comprises a plurality of delivery pumps, and said inlet tube means comprises an inlet tube for each of said delivery pumps.

12. A vapor-entrainment pump, according to claim 9, further comprising cooling means connected to at least part of said shell and of said conveying means adapted for temperature compensation between the vaporized and liquid portions of said fluid.

13. A vapor-entrainment pump, according to claim 9, further comprising an overflow tube leading from at least one of said ejector stages to said reservoir, whereby the excess quantity of the fluid raised by said delivery pump means and said conveying means is returned to said reservoir.
